LEWIS FERRY MOODY, OF PHILADELPHIA, PENNSYLVANIA.

HYDRAULIC TURBINE.

Application filed November 13, 1923. Serial No. 674,461.

This invention relates to hydraulic turbines and particularly to draft tubes for the same. The object of the invention is to provide a draft tube which while simple and inexpensive in construction will be efficient in operation and especially adapted to decelerate the flow within a limited space. Another object of the invention is to provide a draft tube suitable for turbines of high specific speed.

Further objects of the invention, particularly in providing a draft tube structure having a series of concentric annular passages in position below the runner, will appear from the following description and the accompanying drawings.

By dividing the draft tube passage into a number of passages each receiving a part of the total flow, it becomes possible to decelerate the velocity of discharge from the runner and to convert its kinetic energy into useful head within a smaller space than would be possible if a single passage were used, and to accomplish this without sacrifice of draft tube efficiency. The reason why this can be accomplished may be understood by considering a simple passage of rectangular cross-section having a pair of opposite sides diverging at a small angle. Such a passage will decelerate the flow, and it is known that the efficiency of the energy conversion is dependent on the angle of divergence of the sides. If the angle is increased beyond the best value in the effort to produce the deceleration in a shorter length of passage, internal eddies are caused in the flow and the efficiency of conversion is impaired. If, however, a partition is interposed midway between the diverging walls, the angle of divergence between the partition and each wall is cut in half; and each of the new passages thus formed may have the most favorable angle of divergence, and the outer walls of the original passage will then have twice the angle of divergence which would be permissible without the partition. This principle of securing rapid deceleration within a restricted length of passage by subdivision, when applied to conical or flaring annular passages, results in the forms of draft tubes described herein.

Now referring to the drawings:

Fig. 1 is a vertical sectional view of a turbine illustrating the invention.

Fig. 2 is a horizontal sectional view on the line 2—2 of Fig. 1.

Figs. 3 and 4 are vertical sectional views of modified forms and

Fig. 5 is a vertical sectional view showing the turbine of Fig. 4, for instance, in place in the power house.

In the specific embodiment of the invention shown in Figs. 1 and 2 the head cover 7 is supported from the structure 8 at the lower portion of the pit and in turn supports the bearing 9 for the shaft S of the runner R. The flow entering through the intake 10 passes through the adjustable guide vanes 11 and down on to the runner R with whirling components around the turbine axis. The runner is of unshrouded "propeller" type suitable for high specific speed, and is positioned in the upper portion of the passage through the casting 12, the upper end 13 of which is formed to receive and support the guide vanes 11 and operating ring 14. The casting 12 is positioned in the floor 15 of the intake or flume preferably by being set in the concrete so as to form a liner for the draft tube passage. This liner casting 12 flares outwardly from a substantially axial direction at the runner R to a substantially radial direction at its lower end 16.

A central conical core 17 is supported from the foundation floor 15 by rods 18 preferably fastened at their upper ends to the lower end 16 of the liner 12. The central conical core 17 has an outer surface curving from substantially axial at entrance to substantially radial at discharge so that said core is curved convexly toward the axis. Between the outer wall 12 and the inner wall 17 is an intermediate partition 20 separating the draft tube into a plurality of annular passages concentric with the turbine axis and flaring outwardly all around. The walls 12, 20 and 17 are so formed and spaced that the meridian component of the velocity in each annular passage is decelerated as the flow is turned from axial toward radial. (By "meridian component" or "meridian velocity" is meant the velocity in a meridian plane, that is, a plane containing the axis, such as the plane of the drawing, Fig. 1).

If the intermediate partition 20 is placed so that it evenly divides the area between the walls 12 and 17, that is, if the entrance areas of the two annular passages are equal and if

the discharge areas are equal then each passage will produce the same amount of deceleration of the meridian velocity. That is, if substantially half the total flow enters each 5 passage, each half will be decelerated from the same entrance velocity to a common discharge velocity. In order for the entrance areas to be the same, however, the partition will not divide the radial width of the draft 10 tube equally but will fall nearer to the outer wall, so that the product of transverse width of passage and radius to the middle of the passage will be the same in both. At discharge the partition will be midway between 15 the upper wall 16 and the lower wall 17.

In this case of equal subdivision, therefore, it will be noted, first, that the outer passage increases in transverse width in a greater ratio than the inner passage and consequently 20 has a greater average angle of divergence between its outer and inner walls; and, second, the outer passage produces the given amount of deceleration or enlargement of area in a shorter length of passage measured in the 25 plane of the figure. From both considerations it will be preferable to place the intermediate partition nearer the outer and upper wall so that the area across the outer passage is somewhat less than half the total transverse 30 area of the draft tube both at entrance and discharge. This will give more nearly equal efficiency of conversion of velocity head into pressure head in the two passages, and will give a greater total efficiency. It is, therefore, 35 advantageous so to proportion these passages that the inner passage will receive a larger part of the total flow. The entrance end of the intermediate partition 20 is therefore of such a diameter as to make the annular entrance area of the inner passage greater 40 than that of the outer passage.

The intermediate partition 20 in dividing the draft tube into a plurality of passages permits a higher rate of deceleration without 45 departure of the flow from the draft tube surface, because each passage can have the permissible rate of increase in area independent 50 ly of the other passage and the total permissible rate of increase in area is thus approximately doubled, according to the principle 55 previously explained. This makes it possible to accomplish the desired deceleration of the flow within a much shorter length of draft tube, reducing the size and cost of the structure. The walls 12, 20 and 17 being formed 60 as surfaces of revolution offer no obstruction to the whirling components of the outflow, and by smoothly spreading and turning this outflow the annular draft tube passages are adapted to recover both the meridian and whirling components of velocity.

At the discharge from the draft tube the flow will retain some measure of its whirling velocity so that it is preferable as shown in

Fig. 2 to arrange the draft tube to be eccentric with relation to the walls 22 of the outlet 65 passage 23 which outlet passage is thus given somewhat the form of a volute to collect and turn the whirling lines of flow of the discharge from the draft tube. 70

In the turbine shown in Fig. 3 the flow enters through the open flume above the floor 35 and passing through the fixed inclined guide vanes 36 enters the runner R, the guide 75 vanes 36 supporting the central structure 37 carrying the bearing of the runner shaft S. The outer wall casting or liner 42 flares outwardly and at its lower end carries the bolts 43 from which are supported the central conical core 44 and a plurality of intermediate 80 partitions 45 and 46, all of said walls being formed as surfaces of revolution flaring outwardly from axial toward a radial direction at discharge. By thus providing a plurality of intermediate partitions the flow in the draft tube is still further divided and guided and the permissible rate of deceleration between entrance and discharge is still further increased. 85

In the turbine shown in Figs. 4 and 5 the outer wall of the draft tube is formed as a liner casting 52 embedded in the concrete of the floor 48 and at its lower end this liner casting carries the projecting extension 53 of generally conical form and constructed of plate metal bent into the form of a skirt suspended from said casting 52. The central conical core 54 is similarly formed of plate metal bent into the form shown and provided with a cap member 55 under the hub of the runner R. The intermediate partitions 56, 57 are similarly formed of a series of plate sections bent into generally conical form and nested one over the other by lap joints as shown. All of these plate metal members are 90 connected together by the straps or stays 60 at their discharge edges. These stays may be inclined as shown to suit the direction of flow. The flow from the runner is received in a substantially axial direction and turned outward toward a radial direction and decelerated in the upper portion of the draft tube, and in the lower portion of the draft tube the flow is 95 spread and decelerated all around between concentric conical walls. 100

This plate metal construction of the draft tube is inexpensive and easily formed and gives a higher rate of deceleration of the outflow within a small space (see Fig. 5) being suspended from the floor 48 of the flume. This draft tube permits the outlet chamber 110 58 to be of any desired form and, where desired, the central conical core 54 may be continued down to be supported from the floor of this chamber. 115

While the draft tube of this invention is applicable to turbines of all types, it is particularly advantageous for turbines of high 120 125

specific speeds, such as the propeller type turbines shown in the figures. In turbines of low and moderate specific speeds there is a strong tendency at partial gate openings for the discharge to take place through only a part of the runner, namely, that near the outer periphery. The draft tube thus receives a ring of downward flowing water around its outer wall, the inner portion being subject to water not progressing downward but subject to local turbulence and, near the axis, to upward flow into the runner. In turbines of high specific speed, this tendency is still more pronounced, and takes effect through a large range of gate openings and even at normal gate in such turbines the flow through the runner may be very unequally distributed. Attempts to improve the turbine performance by subdividing the runner by the addition of intermediate shroud rings or diaphragms in order to separate the flow into distinct annular zones have not shown any material improvement; and in high specific speed turbines such diaphragms in the runner are very objectionable from the great increase in surface friction which they impose due to the high relative velocity between the runner and the water. I therefore avoid the use of any shroud rings or diaphragms in turbines of high specific speed; and in order to improve the conditions in the draft tube I add one or more partitions or diaphragms in the draft tube.

At times when there is a tendency toward a considerable reduction or a reversal of flow near the runner hub there is at the same time a large whirl or rotational component about the axis in the water below the runner. By providing a separate annular passage for the water in the inner portion of the draft tube, and by leading this passage outward away from the axis so that the water passing through it materially increases its radial distance from the axis in passing from the entrance to the discharge of the passage, I obtain a tube in which the centrifugal force of the contained water sets up an outward pressure and maintains a low pressure at the runner discharge. I also provide a solid core in the central portion of the tube to avoid the extreme conditions of whirl and inefficient flow, and even the creation of a cavity, which are likely to occur near the axis.

In cases where high efficiency is important not only at normal gate but also at part gate, the innermost annular passage is carried outward to substantially the same radius as the outer passage, as in the forms shown in Figs. 1 and 3. When small space and reduced first cost are of more relative importance than part gate efficiency, the form of tube shown in Figs. 4 and 5 may be used, in which the innermost passage is not carried to as great a radial distance from the axis, but a large total area of discharge for the entire draft tube is pro-

vided within a small space. In this form of tube the discharge takes place through almost the whole of the portion of the spherical surface bounded by the discharge edge of the outer wall of the draft tube, the only part of this area which is not utilized for the discharge flow being the relatively small area of the base of the central core, and the space taken up by the thickness of the metal in the partitions.

The structure of this invention provides a turbine of simple and inexpensive form and of small overall dimensions. The suspension of the draft tube from the intake floor avoids the necessity of any special formation of the outlet passage and the short length of the draft tube is particularly adapted for shallow outlets requiring only a limited depth of excavation.

The subject matter disclosed but not claimed in this application is claimed in my co-pending application No. 102,404, filed April 16, 1926.

I claim:

1. A hydraulic turbine having a runner and a draft tube, said draft tube comprising a central core excluding the flow from the central portion of the draft tube, an outer surface curving progressively from a substantially axial direction at entrance to a direction at discharge inclined at a large angle to the axis, and intermediate guiding means cooperating with said core and outer surface to provide a plurality of outwardly directed concentric annular passages surrounding said core and spaced to gradually decelerate the flow.

2. A hydraulic turbine having a runner and a draft tube, said draft tube comprising a central core excluding the flow from the central portion of the draft tube, an outer surface curving progressively from a substantially axial direction at entrance to a direction at discharge inclined at a large angle to the axis, said core and outer surface forming an annular passage continuous with the passage through the runner, and intermediate guiding means cooperating with said core and outer surface to provide a plurality of outwardly directed concentric annular passages surrounding said core and spaced to gradually decelerate the flow.

3. A hydraulic turbine having a runner and a draft tube, said draft tube comprising a central core excluding the flow from the central portion of the draft tube, an outer surface curving progressively from a substantially axial direction at entrance to a direction at discharge inclined at a large angle to the axis, said core and outer surface forming an annular passage continuous with the passage through the runner, and intermediate guiding means cooperating with said core and outer surface to provide a plurality of outwardly directed concentric annular passages surrounding said core and spaced to gradually decelerate the flow.

ually decelerate the flow, the inner passage having a larger width transverse to the flow at entrance than the outer passage.

4. A draft tube for a hydraulic turbine comprising a central core excluding the flow from the central portion of the draft tube and means cooperating with said core to provide a plurality of concentric annular passages surrounding said core, each passage having an outer and an inner surface curving progressively from a substantially axial direction at entrance toward a radial direction at discharge and spaced to decelerate the flow while changing its direction between the runner and said discharge.

5. A draft tube for a hydraulic turbine comprising a central core excluding the flow from the central portion of the draft tube, an outer surface flaring outwardly around said core, and a separate guide member interposed between the core and said outer surface so as to provide a plurality of concentric annular passages progressively curving from a substantially axial direction at entrance toward a radial direction at discharge and formed to decelerate the flow while changing its direction between the runner and said discharge.

6. A draft tube for a hydraulic turbine comprising a plurality of concentric annular passages each passage having outer and inner surfaces curving from a substantially axial direction at entrance toward a radial direction at discharge and spaced to decelerate the flow while changing its direction, the inner passage having a larger entrance area than the outer passage and more gradual rate of deceleration of the flow.

7. A draft tube for a hydraulic turbine comprising a central core excluding the flow from the central portion of the draft tube and means cooperating with said core to provide a plurality of concentric annular passages surrounding said core, each passage having an outer and an inner surface curving progressively from a substantially axial direction at entrance toward a radial direction at discharge and spaced to decelerate the flow while changing its direction and discharging the flow from each passage at substantially the same velocity.

8. A draft tube for a hydraulic turbine comprising a central core excluding the flow from the central portion of the draft tube and means cooperating with said core to provide a plurality of concentric annular passages surrounding said core, each passage having an outer and an inner surface curving progressively from a substantially axial direction at entrance to a substantially radial direction at discharge and spaced to decelerate the flow while changing its direction between the runner and said discharge.

9. In a hydraulic turbine the combination with a turbine support having a water pas-

sage therethrough, of means carried by said support and forming the outer wall of a draft tube, an inner core member carried by said support and an intermediate guide interposed between said outer wall and said inner core member.

10. In a hydraulic turbine the combination with a turbine support having a water passage therethrough, of means carried by said support and forming the outer wall of a turbine draft tube flaring outwardly toward a radial direction, an inner core member carried by said support and flaring outwardly toward a radial direction to provide an annular flaring passage for the flow from the runner and an intermediate guide interposed between said outer wall and said inner core member.

11. A draft tube for a hydraulic turbine comprising a plurality of concentric annular passages each passage having outer and inner surfaces formed as coaxial surfaces of revolution curving from a substantially axial direction at entrance into directions progressively more inclined away from the axis and spaced to decelerate the flow while changing its direction, the innermost surface being provided by a central core member, the contour of the surface of said core member being substantially continuous with that of the runner hub.

12. A draft tube for a hydraulic turbine comprising a plurality of concentric annular passages each passage having outer and inner surfaces curving from a substantially axial direction at entrance toward a radial direction at discharge and spaced to decelerate the flow while changing its direction, the inner passage having an entrance area at least as great as that of the outer passage.

13. A draft tube for a hydraulic turbine comprising a plurality of concentric annular passages each passage having outer and inner surfaces curving from a substantially axial direction at entrance toward a radial direction at discharge and spaced to decelerate the flow while changing its direction, the inner and lower passage having a discharge area at least as great as that of the outer and upper passage.

14. A draft tube for a hydraulic turbine comprising a plurality of concentric annular passages each passage having outer and inner surfaces curving from a substantially axial direction at entrance toward a radial direction at discharge and spaced to decelerate the flow while changing its direction, the inner and lower passage having a larger discharge area than the outer and upper passage.

15. In a hydraulic turbine the combination with a runner of a draft tube comprising a central core member having a contour continuous with that of the runner hub, and a plurality of concentric annular passages around said core.

16. In a hydraulic turbine the combination with a runner of a draft tube comprising a central core member having a contour continuous with that of the runner hub and increasing in diameter away from the runner, and a plurality of concentric annular passages around said core. 10
17. A draft tube for a hydraulic turbine comprising a relatively short single passage adjacent to the runner, a central core, and a plurality of annular passages concentrically disposed around said core and flared outwardly away from the axis said single passage discharging into said annular passages. 15
18. A hydraulic turbine having a runner and a draft tube, said draft tube comprising a central core excluding the flow from the central portion of the draft tube, an outer surface curving progressively from a substantially axial direction at entrance to a direction at discharge inclined at a large angle to the axis, and intermediate guiding means cooperating with said core and outer surface to provide a plurality of outwardly directed concentric annular passages surrounding said core and spaced to gradually decelerate the flow, said guiding means being spaced from said runner so as to leave an undivided passage between said runner and said annular 25
- 30 passages.
19. A hydraulic turbine having a runner and a draft tube, said draft tube comprising a central core excluding the flow from the central portion of the draft tube, an outer surface curving progressively from a substantially axial direction at entrance to a direction at discharge inclined at a large angle to the axis, said core and outer surface forming an annular passage continuous with the passage through the runner, and intermediate guiding means cooperating with said core and outer surface to provide a plurality of outwardly directed concentric annular passages surrounding said core and spaced to gradually decelerate the flow, said guiding means being spaced from said runner so as to leave an undivided passage between said runner and said annular passage. 35
20. In a hydraulic turbine the combination with a runner of a draft tube having inner and outer walls and one or more intermediate partitions subdividing the flow and curved from a substantially axial direction at entrance into directions diverging from the axis, said intermediate partitions having relatively small substantially constant thickness compared to the width of the passages so that substantially all of the area between the inner and outer draft tube walls is utilized 40 for the entire flow. 45
21. In a hydraulic turbine the combination with a runner of a draft tube having inner and outer walls and one or more intermediate partitions subdividing the flow and diverging from the axis in the direction of flow, said 50
- inner wall being in alignment with and forming a continuation of the surface of the runner hub. 55
22. A draft tube for a hydraulic turbine comprising a central core and a plurality of concentric annular passages surrounding said core, the walls of said passages being substantially axial at entrance, and the length of the innermost passage measured in a meridian plane and in the direction of flow being at least equal to that of the outermost passage. 60
23. A draft tube for a hydraulic turbine comprising a central core and a plurality of concentric annular passages surrounding said core, the walls of said passages being substantially axial at entrance, and the length of the innermost passage measured in a meridian plane and in the direction of flow being greater than that of the outermost passage. 65
24. In a hydraulic turbine having a runner, the combination with a sub-foundation structure forming the top of a discharge passage, of a draft tube projecting downward into said passage and comprising a plurality of concentric tubes spreading outward and dividing the flow into a plurality of spreading annular streams, the inner tubes being spaced from the turbine runner to form a common discharge chamber and being supported from the outermost tube which in turn is supported from 70 said sub-foundation structure. 75
25. In a high specific speed hydraulic turbine having a propeller type unshrouded runner, the combination with a sub-foundation structure forming the top of a discharge passage, of a draft tube projecting downward into said passage and comprising a plurality of concentric plate metal tubes spreading outward and dividing the flow into a plurality of spreading annular streams, the inner tubes being spaced from said runner to form a discharge chamber common to a plurality of the passages formed by said tubes and being supported from the outermost tube which in turn is supported from 80 said sub-foundation structure. 85
26. In a hydraulic turbine having a runner the combination with a floor structure, of stay vanes supported thereby and carrying a bearing structure for the runner shaft, a draft tube receiving the flow from said runner and comprising a plurality of concentric tubes spreading outward and dividing the flow into a plurality of spreading annular streams, the inner tubes being supported from the outermost tube which in turn is supported from 90 said floor structure. 95
27. In a hydraulic turbine the combination with a support having a flow passage therethrough, of a runner in said passage adapted to discharge the flow in a substantially axial direction, inclined stay vanes carried by said support and in turn carrying a bearing structure for the shaft to said runner, and a draft tube comprising a central core substantially 100
- 105
- 110
- 115
- 120
- 125
- 130

continuous with the hub of said runner and a plurality of tubes surrounding said core and dividing the flow into a plurality of annular streams spreading outward away from the axis.

28. A hydraulic turbine having a runner and a draft tube, said draft tube comprising an outer surface curving progressively from a substantially axial direction at entrance to a direction at discharge inclined at a large angle to the axis and a central core member, said core and outer surface forming an annular passage continuous with the passage through the runner, and intermediate guiding means cooperating with said outer surface to provide a plurality of outwardly directed passages concentric around the axis of the turbine and spaced to gradually decelerate the flow, said guiding means being spaced from said runner so as to leave an undivided passage between said runner and said annular passages.

29. In a hydraulic turbine the combination with a runner discharging the flow axially, of a draft tube adapted to receive the flow substantially axially and turn it toward a radial direction while simultaneously gradually and continuously decelerating its velocity and comprising an outer spreading wall, and a thin inner partition member of substantially constant thickness continuously curving from axial toward radial between its entrance and discharge ends and dividing the flow into inner and outer streams each of which is decelerated to convert velocity head into pressure head.

30. In a hydraulic turbine installation the combination comprising an unshrouded high specific speed propeller type runner having a hub with vanes radially projecting freely therefrom, and means including relatively thin plate metal members of substantially uniform thickness forming a draft tube having a plurality of substantially annular passages extending radially outward to permit fluid to be discharged substantially horizontally and said passages being adapted to separate the flow and each passage being adapted to continuously decelerate the flow discharged from said runner, and beginning from near the discharge side of said runner.

31. In a hydraulic turbine installation the combination comprising an unshrouded high specific speed propeller type runner having a hub with vanes radially projecting freely therefrom, and means forming a draft tube having a plurality of substantially annular passages extending radially outward to permit fluid to be discharged substantially horizontally and said passages being adapted to separate and decelerate the flow discharged from said runner, and beginning in a substantially axial direction from near the discharge side of said runner and gradually and continuously decelerating and turning toward a radial direction as the discharge end of said passages are approached.

32. In a hydraulic turbine installation the combination comprising an unshrouded high specific speed propeller type runner having a hub with vanes radially projecting freely therefrom, and means forming a draft tube having a plurality of substantially annular passages extending radially outward to permit fluid to be discharged substantially horizontally and the entrance portion of said means forming said passages being spaced from the discharge side of said runner whereby discharged fluid passes through a common unobstructed space prior to entering said passages, and said passages being adapted to separate and decelerate the flow discharged from said runner.

33. In a hydraulic turbine the combination with a runner discharging the flow axially, of a draft tube adapted to receive the flow substantially axially and turn it toward a radial direction while simultaneously gradually and continuously decelerating its velocity and comprising an outer spreading wall, and a thin inner partition member of substantially constant thickness curving from axial toward radial and dividing the flow into inner and outer streams each of which is decelerated to convert velocity head into pressure head, the radius of curvature of said partition in meridian section being materially greater than the radial distance of the entrance portion of said partition from the turbine axis.

LEWIS FERRY MOODY.
